FOOD CONTAINER

Carl M. Piochman, Chicago, Ill.

Application March 8, 1941, Serial No. 382,417

5 Claims. (Cl. 215—38)

The invention relates to sealed food containers and more particularly to containers of the type in which food products such, for example as mustard, cheese, honey, jams, jellies, etc., may be packaged for sale and in which the product may be kept in the refrigerator or pantry shelf by the purchaser for partial consumption from time to time until the product is entirely used up.

It is a general object of the invention to provide a food container of this type embodying novel closure means characterized by its simplicity of construction and use and its effectiveness as an efficient sealing means not only when originally applied to the container by the manufacturer, but also when reapplied numerous times by the consumer.

It is another object of the invention to provide an article of this type embodying a stopper member which has a novel cooperative relation with a sealing member and which, when the food has been consumed, may be utilized alone apart from the sealing means as a cover for the container for storing other foods which do not require sealing.

It is a further object of the invention to provide a new and improved container closure arrangement which operates on the principle of flexing a resilient sealing member into yieldable sealing relation with the container, as distinguished from compression of the sealing member, to the end that it may be easily applied and removed with a minimum force expenditure by the user, yet at the same time provide an efficient sealing effect.

Other objects and advantages of the invention will become apparent as the following description proceeds taken in connection with the accompanying drawing in which:

Figure 1 is an axial sectional view of a container and closure means therefor embodying the features of the present invention as seen in assembled relationship.

Fig. 2 is a fragmentary sectional view similar to Fig. 1 but showing the parts in exploded or disassembled relationship.

Fig. 3 is a plan view of the container and closure means shown in Fig. 1, with a portion of the closure means broken away to reveal the underlying construction.

Fig. 4 is a fragmentary sectional view showing the relationship between the container and stopper apart from the sealing means illustrated in Figs. 1 to 3, inclusive.

While the invention is susceptible of various modifications and alternative constructions, I

have shown in the drawing and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims:

I have illustrated in the drawing merely for purposes of disclosure, a container 10 having a generally cylindrical but slightly tapered side wall 11 and being formed preferably of glass for the purpose of enhancing the appearance of the container so that it may be used as an attractive article of tableware. In this connection the container is designed particularly, but by no means exclusively, for such food products as mustard, cheese, honey and the like which may be partially consumed from time to time, the container being provided with means for effecting a hermetical seal in the meantime. When the contents is completely consumed the container may be reused for sugar, jams, jellies, pickles and the like which do not necessarily require sealing and which may be placed directly on the table in the container.

One of the problems encountered in the use of jars or containers of this type is the provision of a simple yet effective sealing means which is easy for the housewife or other user to apply and remove, and which at the same time will positively assure effective sealing. Many expedients for accomplishing this end have been suggested but all of them either require a considerable force to satisfactorily apply and remove the closure members or if not they are frequently found unsatisfactory for effecting a perfect seal. The well sealed containers customarily used usually rely upon compressing or squeezing the body of a resilient gasket or washer between rigid substantially flat opposed surfaces on the container mouth and cap or stopper member, respectively. Obviously such an arrangement necessitates the use of considerable force sufficient to compress the body of the sealing member. Similarly the removal of closure means sealed in this fashion is frequently extremely difficult.

I have accordingly provided a sealing closure means which operates on a new and different principle and which is effective to overcome the difficulties outlined above. The principle is that of flexing a resilient sealing member by a force applied at a point away from its sealing contact area to exert a yieldable sealing effect at said

area, as distinguished from a compression between two rigid opposed surfaces at said area. Thus, in the instant embodiment, referring more particularly to the drawing, the open, generally cylindrical mouth portion of the container 18 is provided with an internal annular shoulder 12 having a flat upper face 13 disposed slightly below the top of the container. A flexible resilient sealing member 14 of any suitable material such, for example, as cardboard or rubber, and normally having a flat disk-shaped contour (see Fig. 2) is designed to seat peripherally on the face 13 of the shoulder 12 and extend in closing relation to the mouth of the container. A stopper 15, preferably of glass, and having a knob handle 16 has an external diameter dimension less than that of the inner periphery of the mouth of the container but greater than that of the shoulder 12 so that it may fit within the mouth. The stopper is provided with a depending annular flange 17 radially inwardly of its edge and having a diameter dimension less than that of the shoulder 12. Upon application of the stopper 15 to the mouth of the container, the flange 17 is adapted for bearing engagement on the sealing member 14 radially inwardly of the shoulder.

Means are provided for exerting a downward closing force on the stopper so that the depending flange 17, which bears on the sealing member 14 inwardly of its peripheral contact with the shoulder 12, will cause the resilient sealing member to flex and assume a concave or dished shape (see Fig. 1). In the present instance a metallic rim 18 having a depending skirt portion 19 is provided with a plurality of bosses 20 struck on its internal surface. The bosses cooperate with an external ledge or shoulder 21, in the present instance formed by an annular groove in the external wall of the container. The rim 18 is provided also with an internal annular flange portion 22 for engagement with an annular flat face portion 23 on the stopper 15.

The dimensional relationship of the parts is such that after the flexible sealing member 14 and the glass stopper are seated in position and the rim 18 is pressed over the container until the bosses 20 snap into engagement over the shoulder 21, the flange 17 on the stopper will depress the sealing member against the force of its own resiliency to its flexed concave position as seen in Fig. 1. The sealing member is sufficiently resilient so that after the rim has been snapped onto the top of the container the tendency of the sealing member to return to its normal or flat position (Fig. 2) effects a tight yet yieldable sealing relation at its periphery with the upper face 13 of the shoulder member 12, and particularly with the inner peripheral upper edge thereof. Thus, it will be apparent that the sealing effect is caused by a flexing force on the resilient disk 14 at a point away from the sealing area so that the resistance of the disk to flexure results in a yieldable sealing force exerted on the internal shoulder of the container. Such an arrangement creates a permanent and effective seal yet, at the same time, does not require nearly the applying or removing force necessary for a seal of the type wherein a resilient gasket or the like is compressed bodily or squeezed between rigid surfaces.

Referring more particularly to Fig. 4 of the drawing, I have illustrated the relationship of the container and the stopper when used separately apart from the sealing means. After the contents of the jar, as originally packaged, is con-

sumed, the container may be refilled with various food products such as sugar and the like, not requiring sealing. The depending annular flange 17 on the stopper, being dimensioned to engage the sealing member radially inwardly of the shoulder 12 on the container, is designed to fit within the shoulder 12 after the sealing member 14 and the rim 18 have been discarded. In this position shown in Fig. 4, the flange in cooperation with the shoulder 12, serves the purpose of centering or interfitting means which provides an efficient, though unsealed, closure for the container.

It will be apparent from a consideration of the foregoing that a novel and advantageous container structure has been provided which is simple and accordingly inexpensive to manufacture, which has marked sealing advantages attainable by a simple manipulation requiring but slight effort for both applying and releasing, and which utilizes part of the novel means for effecting such seal to provide a suitable closure means for the container when refilled with a food product which does not require sealing.

I claim as my invention:

1. A container for food products including, in combination, a mouth portion having an internal shoulder formed thereon, a sealing member formed of a resilient material seated on said shoulder in closing relation to said mouth portion, a rigid stopper bearing on said sealing member inwardly of said shoulder, said mouth portion having an external groove formed therein, and a clamping member having means adapted for holding engagement in said groove and an inner peripheral flange adapted for engagement with said stopper, the dimensional relationship of said groove, holding means, flange, stopper and shoulder being such that, upon engagement of said holding means with said groove, said stopper will be depressed against the resiliency of said sealing member causing it to assume a concave position in which a yieldable sealing thrust is exerted on said shoulder by the marginal edges of said sealing member.

2. A glass container for food products including, in combination, a cylindrical mouth portion having an internal annular shoulder formed thereon, a disk-shaped sealing member formed of a resilient material peripherally seated on said shoulder in closing relation to said mouth portion, a glass stopper having an annular depending flange adapted for engagement with said sealing member radially inwardly of said shoulder upon application of said stopper to the mouth of the container, and means for holding said stopper in a depressed position against the resiliency of said sealing member causing it to assume a concave position, said stopper being adapted to seat on said shoulder with said flange fitted within said shoulder when said holding means and said sealing member are no longer employed.

3. A container for food products including, in combination, an annular shoulder defining the mouth portion of said container, a disk-shaped sealing member formed of a flexible resilient material seated on said shoulder in closing relation to said mouth portion, a closure member having an annular depending flange adapted for engagement with said sealing member radially inwardly of said shoulder upon application of said closure member to the mouth of said container, and means for exerting a predetermined downward closing thrust on said closure member to a posi-

tion in which said sealing member is flexed downwardly to a concave position, such position constituting the permanent sealing position of said sealing member in which the peripheral edge thereof acts to exert, through its resiliency, a yieldable sealing thrust on said shoulder and from which position said peripheral edge is free to yield upwardly.

4. A structure of the character described comprising, in combination, a receptacle having an annular internal horizontal ledge spaced downwardly from its open upper end and having external locking means to interengage with a clamping device, a flexible sealing disk fitting within said open end and bearing upon said ledge, a closure fitting within said upper end and having a downwardly projecting annular flange on its lower face spaced a substantial distance inwardly from its perimeter and resting upon the upper face of said disk a slight distance inwardly from said ledge, and an annular clamping device surrounding the upper end of said receptacle and comprising an inwardly-extending flange portion overlying said closure and a skirt portion fashioned to snap into engagement with said locking means when said device is pressed

5. A structure of the character described comprising, in combination, a receptacle having an annular internal ledge spaced downwardly from its open upper end and having an external locking shoulder, a flexible sealing disk fitting within said open end and bearing upon said ledge, a closure fitting within said upper end and having a downwardly projecting annular flange spaced inwardly from its perimeter and resting upon

10 said disk a slight distance inwardly from said ledge, and clamping means engaging said closure and the locking shoulder on said receptacle, said clamping means when in operative position exerting a downward pressure on said closure and causing the said flange thereon to exert a downward pressure on said disk to flex the latter into concave form and thereby insure sealing contact between said sealing member and said ledge.

CARL M. PLOCHMAN.
